UNITED STATES PATENT OFFICE.

GEORGE WASHINGTON MELOTTE, OF ITHACA, NEW YORK.

BLOW-PIPE BED.

SPECIFICATION forming part of Letters Patent No. 400,103, dated March 26, 1889.

Application filed July 30, 1888. Serial No. 281,419. (No model.)

To all whom it may concern:

Be it known that I, GEORGE WASHINGTON MELOTTE, a citizen of the United States, residing at Ithaca, in the county of Tompkins and 5 State of New York, have invented a new and useful Soldering Pad and Stand with a Melting-Cavity, of which the following is a specification, reference being had to the accompanying drawings.

10 My invention relates to an improvement in soldering pads and stands; and it consists in the peculiar construction and combination of devices that will be more fully set forth hereinafter, and particularly pointed out in the 15 claims.

In the accompanying drawings, Figure 1 is a top plan view of my improved pad or cushion. Fig. 2 is a side elevation, partly in section, of the cushion and supporting-stand. 20 Fig. 3 represents the bottom of the melting-cup. Fig. 4 is a perspective view of the mold. Fig. 5 is a vertical sectional view of the pad, taken on the line $x-x$ of Fig. 1, and showing the melting-cup in the excavation. Fig. 6 is 25 a plan view of the reverse side of the pad, showing a broken key and thimble clamped to the bed in position for repairing. Fig. 7 is a plan view of the modified form of bed, showing the melting-excavation more centrally located and the mold clamped against the flat face of the band b . Fig. 8 is a side elevation of the modified form shown in Fig. 7.

The pad or cushion is made of a continuous ribbon of asbestos cloth or paper, a , wound 35 upon itself, as indicated by the circular lines in Fig. 1.

The preferred diameter of the pad for dentists' and jewelers' use is from three and one-half to five inches, and the thickness of the 40 pad is preferably from five-eighths to an inch.

Around the perimeter of the pad is a metallic band, b , preferably of brass or iron, which prevents the ribbon of asbestos from 45 uncoiling and renders the pad compact. In the upper side of the pad, near one edge thereof, is made a concave recess, c , substantially in the form of a clam-shell. This recess is formed by forcing the asbestos layers downward by pressing on the same with the 50 thumb and removing or cutting away the por-

tions of the layers which are below the plane of the pad.

In one side of the recess c is a curved extension, c^5 , which serves the purpose of holding the spout of the crucible or cup. In the 55 bottom of the recess c are holes c' . When a blow-pipe is used as the source of heat these openings are plugged with asbestos; but when a Bunsen burner is used, as shown in Fig. 2, they are left open, and in this case a 60 removable cup or crucible, c'' , is employed, which is so shaped that it is adapted to lie in the recess c , with its spout in the extended recess c^5 . This cup or crucible is made of 65 fire-clay, sand, and borax, or other refractory substances, and is hardened in the recess c when dry. This cup or crucible has radial ribs c^4 on its bottom, which bear against the bottom of the recess c , and thereby cause a space between said recess and the cup into 70 which the flame from the burner enters, thus enabling the cup to be heated to a very intense degree. The lower side of the pad is perfectly flat and has no recess or indentation, and lies upon four or more radial arms, 75 e , that extend to the edge of the pad, and are bent upward at their outer ends, which bear on the edge of the pad, as shown in Fig. 2. The pad may be removed from these arms and reversed—that is to say, either side of 80 the pad may be turned up.

My construction of the pad, by forming the same of a coiled asbestos ribbon, renders the pad sufficiently compact and dense, and yet allows pins and clamping devices to be inserted between its coils at any portion of its surface without injury thereto. The pad acts as a cushion, and the asbestos-coils make a durable level surface, and yet do not allow melted metal to sink into the pad. The pad 90 is also peculiarly adapted to retain the heat while in use.

The ingot-mold c^6 is rectangular in form, has plane surfaces, and has two cavities on one side and one on the other, as shown, and 95 is adapted to be clamped on the upper side of the pad, with either side of the mold presented to the same, and with the mouth of either of its cavities presented to the spout of the cup or to the recess extension c^5 , so 100

that when the pad is tilted the metal in the cup or recess will flow into the mold.

Surrounding the metallic band *b* is a **V**-shaped or dovetailed ring, *f'*, on which are several movable pieces, *f''*, which have dove-tailed recesses engaging the ring, and are adapted to slide on the latter, so that the clamps may be grouped together or dispersed on all sides of the pad, as may be desirable. 5 Spring clamp-arms *f* are inserted in openings in the slide-pieces *f''*, and are adapted to retain the ingot-mold or other necessary articles on the pad. Pin-clamps *f⁵* are stuck into the asbestos pad between the layers or coils thereof, and are also useful to retain the 10 mold and other articles on the pad.

The circular form of the pad may be changed by flattening the same on one side, thus making the shape of the pad as shown by Fig. 1. 20 The mold may be then secured in an upright position on the flattened side of the band *b*, which will in this instance be provided with a downturned extension or arm, *b'*, to bear against the inner side of the mold, as shown 25 in Fig. 5. No means are herein shown to secure the mold in this position to the pad, as common screw-clamps or other means, such as will readily suggest themselves, may be employed for this purpose. When thus arranged, the mold is brought near the recess *c*, when the latter is made in the center of the pad, and the molten metal may be flowed from the recess to the mold by tipping the pad, as in the previous instance. A handle, *k*, is fast 30 to one side of the pad-band *b*, by means of which the pad can be readily lifted and either side placed up. The centers of the arms *e* are fast to a cap, *g*, which is flat on its lower side and has a slot, *g'*, in which the round-topped 35 tenon of the rod *h* is inserted and held by a pin, *g''*, thus making a hinge-joint. The rod *h* is inserted in the cavity or bore *i'* of the stand *i*, and, being round, the rod, its arms *e*, and the cushion or pad may be freely rotated. 40 On the lower portion of the rod *h* is a spiral spring, *j*. The upper end of the spring bears against a shoulder, *i'''*, of the bore of the stand, and to regulate the tension of the spring a nut, *j'*, is screwed on the threaded lower end 45 of the rod *h*. By this means the spring exerts a constant downward pressure on the rod, which serves to retain the pad normally in a horizontal position, yet permits the pad to be tilted against the pressure of the spring, as 50 will be readily understood.

The Bunsen burner *d* comprises a plain gas-faucet, *d'*, fast to the stud *d''* of the base of the stand, with a fish-tailed or other burner, *d'''*, and a loose piece of pipe, *d⁴*, about the burner *d'''*, having an air-entrance, *d⁵*. 60

Having thus described my invention, I claim—

1. The pad consisting of an asbestos ribbon or strip coiled upon itself, whereby pins may be inserted between the layers or coils of the 65 pad, for the purpose set forth, substantially as described.

2. The pad consisting of tightly-coiled asbestos ribbon, and having the inclosing-band *b* on its perimeter, substantially as described. 70

3. The combination of the stand, the rod therein, the spring bearing downward on the rod and reacting at its upper end against the stand, the holding-arms *e*, having the cap *g*, hinged to the upper end of the rod, and the 75 pad supported on the arms, substantially as described.

4. The revoluble asbestos block *a*, supported on the stand and provided with the excavation *c*, and aperture *c'* in the excavation, and the Bunsen burner *d*, fast to the stand *i* and arranged to register with the aperture *c* when the block *a* is rotated. 80

5. The stand *i*, provided with the round rod *h* in its upright post, in combination with the 85 arms *e*, the pad *a*, and the cap *g*, its joint made by the tongue *g'* of rod *h* in the slot of the cap and with the spring *j*, and the cap resting on the top of the post of the stand, whereby the arms *e* and the cushion-block *a* may be 90 tipped, as set forth.

6. The movable cup *c'''*, provided with the ribs *c⁴* on its under side, in combination with a perforated excavated cup, *c*, in the block *a*, and a Bunsen burner, *d*, the said parts being 95 suitably supported by the stand *i*, as set forth.

7. The combination of the ingot-mold *c⁶* with the block *a*, having the excavation *c* and aperture *c'*, and the removable cup *c'''*, as set forth. 100

8. The cushion *a*, flat on one side and provided with a band, *b*, having a portion, *b'*, at right angles to the plane of the cushion, the mold *c⁶*, and means for securing the mold to portion *b'*, in combination with the cup *c'''*, 105 having spout *c⁵*, as set forth.

GEORGE WASHINGTON MELOTTE.
